UNITED STATES PATENT OFFICE.

FRANK HOWARD GRAHAM, OF BROOKLYN, NEW YORK, ASSIGNOR TO WESTERN ELECTRIC COMPANY, INCORPORATED, OF NEW YORK, N. Y., A CORPORATION OF NEW YORK.

TRANSMISSION CONTROL.

Application filed December 24, 1923. Serial No. 682,507.

This invention relates to electric wave transmission and particularly to controlling the quantity and characteristic of transmission through a system. 55

In testing the hearing, more especially that of deaf persons, valuable information can be obtained by measuring the sensitivity of the ear to a plurality of pure tones extending in pitch throughout the range of 60 audibility. The normal range of hearing with respect to both intensity and pitch has been determined by measurements on a large number of persons and has been charted and discussed by Fletcher in the Bell System 10 Technical Journal, Vol. II, No. 4, October, 15 1923, pages 145 to 180. In the same article, the author shows that the type of deafness as characterized by the responsiveness of the ear to tones of different pitches varies considerably amongst individuals and that 20 considerable aid in the diagnosis of abnormal hearing may be obtained from the results of such measurements. 25

In accordance with this invention, an apparatus for ear analysis is provided whereby a large number of tones may be produced of known pitch and of variable energy, the amount of which is known either relatively or absolutely. 30

In making tests to determine the intensity of sound energy corresponding to the limit of hearing, it is desirable, since the limit may vary greatly for different pitches, to use a pure tone and also to prevent the possibility of a frequency other than that desired for the particular test being produced by an improper manipulation of the apparatus. A vacuum tube oscillator may be used as a dependable source of oscillation 35 for the production of pure tones different pitches being secured by the use of a multiplicity of tuned circuits. The frequency of oscillation and hence the pitch of the tone may be controlled by a set of keys 40 each one of which may be operated to connect a different tuned circuit into the oscillator circuit. Further, in accordance with 45 this invention these keys may be so interconnected that whereas the operation of any one key by itself establishes oscillations of a particular frequency the operation of two or more keys together breaks the oscillator circuit in such a way that no oscillations 50 can be generated. Accordingly, it is a par-

ticular object of this invention to provide an apparatus for the generation of pure tones definitely determined as to pitch and incapable of being operated to produce a tone other than that desired. 55

A further object of this invention is to provide in an apparatus for ear analysis increased precision in the determination of the threshold condition of audibility, or the degree of intensity as measured by the energy of the sound waves at which a tone becomes just audible. 60 When the intensity of a tone is near the threshold value its audible effect may, if the tone is continuous, be readily obscured by anything that may distract the attention of the subject, with the result that widely varying results may be found. Interruption of the tone at intervals serves to aid attention of the subject and so permit a more accurate determination of the limiting intensity. It is necessary 65 that the attention of the subject be directed exclusively to judging the presence or absence of an audible tone and his judgment must not be aided by the possibility of his observing other effects concurrent with the interruption of the tone. It is commonly 70 the case that in an electrical system for the production of audible tones the interruption of the electric current produces an audible 75 click due to the sudden discharge of energy stored in the reactive portions of the circuit. The character of such a transient being greatly different from that of the steady tone its audibility is not in general related 80 to the audibility of the tone and may persist after the threshold condition of the tone has been reached and passed with the result that 85 a false determination may be made. This difficulty is avoided by causing the oscillations to be stopped by the interruption of 90 a non-reactive or substantially non-reactive 95 branch of the oscillator circuit.

The above and other objects of the invention will be clearly understood from the following detailed description and claims taken in connection with the accompanying drawing in which 100

Fig. 1 represents a complete system embodying the invention and 105 Fig. 2 shows an alternative method of interrupting the tone by changing the resistance of the anode circuit of a vacuum tube oscillator.

Referring to the drawing by reference numerals 1 is an energy amplifying device to be described later in detail. The electrodes 4 and 2 constitute terminals for the input of energy and electrodes 3 and 2 output terminals from which amplified energy is delivered.

The amplifier 1 may be caused to generate oscillations in a manner that is well known and understood by feeding back to an input circuit connected to the input terminals part of the energy delivered to an output circuit connected to the output terminals or electrodes 3 and 2. The frequency of the oscillations may be determined by the constants of a tuned circuit connected in either the output circuit or the input circuit or mutually connected to both.

In this invention selective networks 8 each comprising an inductance 9 and a condenser 10 are arranged to be connected one at a time to the amplifier 1 by means of keys 12, 13, 14 and 15. A plurality of oscillation circuits is thereby provided each having a tuned circuit connected in the amplifier output circuit in which oscillations are set up of a frequency determined by the constants of the elements 9 and 10 and from which energy is fed back to the input circuit by means of an inductively coupled coil 11. The constants of the various tuned circuits 9, 10 are adjusted so as to provide oscillations at frequencies corresponding to a series of tones extending through the range of audibility.

A parallel branch of the output circuit of the amplifier includes the primary winding 19 of a transformer 18, the secondary winding 20 of which is connected through an adjustable attenuating device 21 to a jack 22 into which may be inserted a plug 23 thereby completing the connection to a telephone receiver 24.

Various forms of the attenuating device 21 may be used but it is essential that in view of the wide range of intensities to which the ear is responsive that the device be capable of producing a large degree of attenuation. It is also desirable that the degree of attenuation be substantially independent of the frequency, for which reason it is desirable to make the attenuator non-reactive at all frequencies. The form shown in the drawing is that described in the application of R. L. Wegel Serial Number 483,533, filed July 9, 1921. In this form equal resistances 28 and equal resistances 29 are arranged to form a repeated ladder-like circuit structure the resistances 28 being connected in series in one side of the circuit and the resistances 29 being connected in shunt across the circuit to a common lead 27. Contact points 25 are connected to the junction points of the series and shunt resistances contact with any one of which may be made by an adjust-

able contact arm 26. If an electromotive force is applied to the terminals at one end of this ladder-like circuit the potential difference between any contact point and the common lead 27 is readily determined from the values of the resistances and if the circuit had an infinitely great number of sections the potentials of the successive contact points with respect to the common lead would be related to each other as the terms of a geometric series, whereby the estimation of the potential differences corresponding to the various points is rendered simple. The effect of an infinitely prolonged ladder-like circuit may be secured by making the resistance of the final shunt resistance 40 equal to

$$\sqrt{R_1 R_2 + \frac{R_1^2}{4} - \frac{R_1}{2}}$$

in which R_1 is the resistance of each series resistance element 28 and R_2 the resistance of each shunt element 29. The proof of this may be demonstrated by the application of the formulae given in Patent No. 1,227,113 patented to G. A. Campbell May 22, 1917.

In the apparatus of this invention energy from the transformer 18 is supplied to the attenuator and the receiver 24 is arranged to be connected through plug 23 and jack 22 to the contact arm 26 and the common lead 27. The fact that receivers of the type employed in this invention have a finite impedance usually about 200 ohms makes it necessary that the resistances R_1 and R_2 be small in order that the geometric or logarithmic relationship between the potentials of the successive contacts be not seriously disturbed by the presence of the shunt path through the receiver. The effective resistance of the ladder-like network offered to the energy from the transformer 18 is equal to

$$\sqrt{R_1 R_2 + \frac{R_1^2}{4} + \frac{R_1}{2}}$$

and if the values of R_1 and R_2 are so proportioned as to make this quantity equal to about 15 ohms it is found that the relationship is maintained with sufficient accuracy.

The method whereby the generation of oscillations of improper frequencies is prevented will now be described.

A common terminal of each of the selective networks 8 is connected to a common lead which in turn is connected to the electrode 2 of the amplifier common to both output and input circuits. The other terminals of the inductance coils 11 and the tuned circuits 9—10, are connected respectively to contact elements 30 and 31 of the keys 12, 13, 14 and 15 one of which is associated with each network. When the keys are not operated

these contact elements are insulated and the selective networks are disconnected from the oscillator circuit.

Associated in each key with contact element 30 are two contact elements 32 and 33 which are in contact when the switch is not operated but which are separated when the keys are operated by the operating devices 16, contact then being made between the elements 30 and 32. Contact elements 34 and 35 are likewise associated with element 31 in each key, contact being made between the elements 34 and 35 when the keys are not operated and between 34 and 31 when the keys are operated.

A circuit connected to amplifier electrode 4 is connected to the transfer element 32 of key 12 and is continued from element 33 to the transfer element 32 of key 13 and so on passing through the various keys in the sequence 12, 13, 14, and 15.

In like manner a circuit starting from the output electrode 3 of the amplifier passes through the keys in the reverse sequence 15, 14, 13, 12 including in each key the contact elements 34 and 35.

These two circuits may be terminated at the last keys of the sequence or they may be returned to the common electrode 2.

The operation of one of the keys, for example 13, separates the contacts between elements 32 and 33, and between elements 34 and 35 thereby breaking the continuity of both of the above mentioned circuits. Further, the contacts of elements 32 and 34 are transferred respectively to elements 30 and 31 thereby connecting the selective circuit associated with key 13 to the input and output terminals of the amplifier and causing oscillations to be established. It will be noticed that the connection of the particular network selected by the key to the amplifier input and output terminals is established by two circuits one of which passes through all keys of lower numbers in the sequence and the other of which passes through all keys of higher numbers in the sequence. Both circuits are essential to the sustaining of oscillations and consequently the operation of any one other key will suffice to stop the oscillations. Further, since each key acts in a like manner with respect to all of the others it is evident that oscillations can be generated only when one key and when one key only is operated.

From the foregoing description it is evident that a specific form of energy amplifying device is not essential to the operation of the invention but in the preferred form of the invention a three-electrode thermionic vacuum tube is used, the electrodes 2, 3 and 4 being respectively the cathode, anode and control electrode. The cathode consists of a filament heated by current from a battery 5 in a circuit connected to its terminals.

Energy for the space discharge is furnished from a battery 6 connected through a high impedance choke coil 7 to the anode 3. A condenser 17 prevents current from this battery from passing into the output circuits 70 including the transformer 18 and the selective circuit 8.

Starting and stopping the oscillations is accomplished also by the operation of key 37 a resistance 39 being inserted in series 75 with the heating battery 5 when the key contact is opened. The resistance 39 is of such value as to reduce the heating current and hence also the temperature of the filament to a point at which oscillations cannot be sustained. The filament circuit is practically non-reactive so that there is no discharge of stored energy at the instant the current is changed and consequently no noise producing transient. The attainment of this result is aided by the fact that the temperature of the filament changes relatively slowly thus preventing any abrupt change in the oscillation amplitude. Two resistances 38 are connected in series across the terminals 80 of the filament and the common leads of the input and output circuits are returned to the mid-point of these resistances. This arrangement serves to insure that the control electrode 4 is connected to a potential corresponding to the mid point of the filament thereby changes in the potential difference between the filament terminals produce no effect on potential of element 4 relatively to the cathode mean potential and therefore 100 cannot affect the oscillation through the agency of the control electrode.

Referring to Figure 2, a resistance 39 is connected in the common connection between the anode and the selective circuits. This resistance is short circuited by a circuit through the contact of the key 37 and is inserted in the circuit by opening the key contact. Its value is made sufficiently large to stop the oscillation of any of the circuits so that by opening and closing the key circuit oscillations are stopped and started at will. The anode circuit in which the resistance is inserted includes the space discharge path within the vacuum tube, a resistance 36, the purpose of which will be described later, and a parallel tuned circuit 9-10 whose impedance at resonance is high and practically purely resistive. The absence of reactance from this circuit results in freedom from 110 stored energy therein which would be dissipated in a noise producing transient at the moment of manipulating the key.

The resistances 36 connected in series with each tuned circuit are provided for an initial adjustment of the energy of the oscillations corresponding to each tone. It is desirable that for any given setting of the attenuator the energy converted into sound energy by the receiver 24 should be the same for each 120

frequency. This condition may be secured by adjusting the resistances to a proper value.

If the receiver were uniformly efficient as a convertor of energy at all frequencies, it would be sufficient that each oscillation circuit be adjusted by means of resistances 36 until equal currents were delivered to the attenuator 21. However, the receiver may not be uniformly efficient with the result that with the same voltage applied to its terminals different intensities of sound, as measured by the sound wave energy, would be produced at different frequencies. It is necessary therefore that the efficiency of the receiver as a convertor of energy be known at the different frequencies of the oscillator.

This may be determined by comparing the receiver with a fundamental standard in which the conversion efficiency can be definitely determined from simple measurements. Such an apparatus is the thermophone described by Arnold and Crandall in the Physical Review, volume 10, number 1, July 1917.

With the efficiency of the receiver determined at the various frequencies the resistances 36 may be made of the correct value so that the intensity of oscillations at each frequency corresponds to a uniform amount of sound wave energy produced by the receiver.

From the foregoing description the method of operation of the invention is readily evident.

The receiver 24 is connected into circuit by means of plug 23 and jack 22 and is applied to the ear, an analysis of which is to be made. One of keys 12-13-14-15 is operated connecting the corresponding tuned circuit into the oscillator circuit whereby oscillations are started and a tone of the selected pitch is produced by the receiver.

By turning the contact arm 26 of the attenuator 21 to the contact point nearest in the circuit to the oscillator, the full voltage of the transformer is applied to the receiver and a loud tone is produced. If this tone produces an audible sensation the contact arm is moved over the other points thereby increasing the amount of energy attenuation and correspondingly diminishing the intensity of the tone. The rotation of the arm is continued until a position is reached for which the tone is just perceptible. Interrupting the oscillations at intervals by the manipulation of the key 37 assists in the judgment of the degree of attenuation needed to produce the just perceptible tone intensity in accordance with the principle discussed in the foregoing text.

Obviously it is necessary that the subject of the ear analysis should not manipulate the tone interrupting key otherwise his attention being directed to the manipula-

tion of the key would be diverted from the perception of the tone and inaccurate determinations would result.

What is claimed is:

1. An electrical oscillator particularly adapted for use in apparatus for the analysis of hearing comprising an amplifying device, a plurality of fixed tuned circuits, and circuits including keys for connecting said tuned circuits respectively in operative relation to said amplifier, the contacts of said keys being so interconnected that the simultaneous operation of more than one key prevents the generation of oscillations by interrupting an essential branch of the oscillator circuit.

2. An electrical oscillator comprising an amplifying device, a plurality of fixed tuned circuits, circuits including keys for connecting said tuned circuits respectively in operative relation to said amplifier, and means effective upon the operation of any one of said keys to interrupt a connection between said amplifying device and all others of said keys, whereby the establishment of oscillations of other than the desired frequency is prevented.

3. An electrical oscillator comprising an amplifying device having input terminals and output terminals, a plurality of fixed tuned circuits, keys associated with said tuned circuits respectively, and circuits including said keys for connecting said tuned circuits in operative relation to said amplifier, said connecting circuits including a circuit connected to an input terminal of the amplifier and passing in sequence through normally closed contacts in each of said keys, and a circuit connected to an output terminal of the amplifier passing in the reverse sequence through separate normally closed contacts in said keys, whereby upon the operation of any one key the connection is interrupted between the amplifier and all others of said keys.

4. In an apparatus for the analysis of hearing by the determination of the limiting energy of sound waves required to produce a sensation of sound, an electrical oscillator adapted to generate oscillations at a plurality of fixed audio frequencies comprising in combination an amplifying device, a plurality of fixed tuned circuits, keys associated with said tuned circuits respectively, circuits including said keys for connecting said tuned circuits in operative relation to said amplifier and impedances associated respectively with said tuned circuits to adjust to a uniform intensity the oscillations of the several fixed frequencies.

In witness whereof, I hereunto subscribe my name this 22 day of December, A. D. 1923.

FRANK HOWARD GRAHAM.
